UNITED STATES PATENT OFFICE

141,244

DESIGN FOR A DIESEL ENGINE

John Thysse, Alameda, Calif.

Application August 12, 1942, Serial No. 107,918

Term of patent 14 years

(Cl. D77—1)

To all whom it may concern:

Be it known that I, John Thysse, a citizen of the United States and a resident of Alameda, county of Alameda, State of California, have invented a new, original, and ornamental Design for a Diesel Engine, of which the following is a specification, reference being had to the accompanying drawing, forming part thereof.

Figure 1 is a perspective view of the Diesel engine showing my new design.

Figure 2 is a view similar to Figure 1, but from an opposite angle.

I claim:

The ornamental design for a Diesel engine, substantially as shown.

JOHN THYSSE.
